UNITED STATES PATENT OFFICE.

THOMAS KENDRAY, OF SARNIA, ONTARIO, CANADA, ASSIGNOR OF ONE-HALF
TO GEORGE N. MATHESON, OF SAME PLACE.

TUG-STRAP HOLDER FOR LOOMS.

SPECIFICATION forming part of Letters Patent No. 405,418, dated June 18, 1889.

Application filed September 27, 1888. Serial No. 286,528. (No model.) Patented in England August 20, 1888, No. 11,990.

To all whom it may concern:

Be it known that I, THOMAS KENDRAY, a subject of the Queen of Great Britain, and a resident of Sarnia, in the Province of Ontario, 5 Canada, have invented certain new and useful Improvements in Tug-Strap Holders for Looms, (for which I have obtained a patent in Great Britain, No. 11,990, bearing date August 20, 1888,) of which the following specification, taken in connection with the accompanying drawings, forms a full, clear, and exact 10 description.

This invention relates to improvements on tug-strap holders for looms, and particularly 15 to an improvement on a sliding tug-strap holder for power-loom for which a United States Patent No. 351,779 was granted to me on the 2d day of November, A. D. 1886; and this invention consists of devices for rigidly 20 and firmly securing the tug-strap holder at the position to which it is adjusted on the picking-stick to completely prevent any possibility of the sliding tug-strap holder or its securing devices from becoming accidentally 25 displaced under any circumstances whatever, as will be hereinafter more fully described and claimed.

Reference is had to the accompanying drawings already mentioned, wherein— 30 Figure 1 is a side elevation of a tug-strap holder, as well as of its securing devices, as applied to a picking-stick. Fig. 2 is an edge view of the same, showing the securing devices disengaged from each other. Fig. 3 is 35 a side elevation of a modification of the tug-strap holder and plate-fastener shown in Fig. 1. Fig. 4 is an edge view of same, showing the tug-strap holder partly in section and the plate-fastener disengaged therefrom.

40 In operating the invention illustrated in my United States patent, hereinbefore mentioned, I find that the jar of the picking-stick D is liable to displace the nut E', mentioned therein, and thereby loosen the sliding tug- 45 strap holder A. If the nut E' were accidentally displaced by the jar of the picking-stick, the tug-strap holder A would also become loose on the picking-stick. The operator would then have to pass around and be 50 continually tightening the nut E', which

would not only occupy considerable time, but would necessitate the stopping of the loom. Now, all this is completely prevented by using my invention, hereinafter described.

In the annexed drawings, D designates the 55 picking-stick; A, the tug-strap holder formed with a slot F, eye A', and flange A"; and E, the bolt passing through slots or openings in the sliding tug-strap holder and picking-stick, all of which are fully described in the patent 60 hereinbefore mentioned.

This improvement consists of a thumb-nut or its substantial equivalent E', rigidly secured to which or formed integrally therewith is a ratchet R, for the purpose of rigidly holding the ratchet R in place and to prevent it from turning when it is bound aga'inst the plate-fastener G.

G designates a plate-fastener, interposed 70 between the ratchet R and tug-strap holder A. This plate-fastener G is provided with projections P, which loosely engage with corresponding recesses H in the tug-strap holder A, as shown in Figs. 3 and 4. These projections P may engage with recesses H between 75 cogs J on the holder A, as in Figs. 1 and 2, or the projections P may be formed on the tug-strap holder A and the recesses H formed in or on the plate-fastener G, as found most 80 suitable or convenient under the circumstances, so that when the thumb-nut E' is tightened these projections P engage with the recesses H and firmly hold the plate-fastener G in place on the tug-strap holder A, and at the same time prevent either from 85 moving independently of the other.

K designates a pin or bolt, rigidly secured to or formed integral with the plate-fastener G, and L is a dog pivoted on this pin or bolt K, and between this dog L and a shoulder 90 or overhanging head K' of this pin or bolt K a coil-spring N is interposed, as shown in Fig. 2 of the accompanying drawings, and this pin or bolt K is secured in proper position on the plate-fastener G, so that the outer end of 95 the dog L will engage with the ratchet R. This coil-spring N is for the purpose of preventing the accidental displacement of the dog L from the plate-fastener G; and S is a flange or stud formed on the plate-fastener G to pre- 100

vent the dog L from being accidentally moved laterally from engagement with the ratchet R. The jar of the picking-stick D when in operation is liable to displace this dog L if not firmly held and secured in place by the spring N and stud or flange S. At the same time, when it is required to adjust the sliding tug-strap holder A up or down on the picking-staff D, to cause the latter to give a more or less forcible pick, the spring N permits the dog L to be grasped by the hand and moved from the plate-fastener G, thus compressing the spring N until the dog L clears the stud or flange S, when the dog L may be moved out of the way of the ratchet R to the position shown in Fig. 2. This permits the loosening of the thumb-nut E' and ratchet R from the plate-fastener G, and permits of the adjustment of the tug-strap holder to the proper position, so that the picking-stick will give the required pick. When properly adjusted, it is held in that position by adjusting the plate-fastener so that the projections P will come opposite the recesses H, and by turning the thumb-nut E' until the lower side of the ratchet R binds the fastener and tug-strap holder firmly together. This ratchet R is then locked in that position by lifting the dog L until it clears the stud or flange S and engages with the ratchet R between the latter and the flange or stud S and spring N.

This invention has been described as securing a tug-strap holder to a picking-stick, but it would work equally well in securing and locking other objects together.

Having thus described my invention, I claim—

1. A plate-fastener G and a tug-strap holder A, one having recesses H and the other projections P, fitted loosely to said recesses, in combination with means for clamping them together and to the side of a picking-stick, as and for the purpose set forth. 40

2. The stud or flange S, in combination with the plate-fastener G, pin or bolt K, having head or shoulder K', spring N, dog L, thumb-nut E', ratchet R, and bolt E, as and for the purpose set forth. 45

3. A plate-fastener G and a tug-strap holder A, one having recesses H and the other projections P, fitted loosely to said recesses, in combination with a picking-stick and means for clamping them together and to the side of the picking-stick, as and for the purpose set forth. 50

4. A plate-fastener G and a tug-strap holder A, one having recesses H and the other projections P, fitted loosely to said recesses, in combination with a ratchet R, thumb-nut E', bolt E, picking-stick D, dog L, spring N, pin K, formed with shoulder K', and stud or flange S, as and for the purpose set forth. 55 60

In testimony whereof I affix my signature in the presence of the two undersigned witnesses

THOMAS KENDRAY.
